UNITED STATES PATENT OFFICE.

JOHN MODINI, OF WASHINGTON, DISTRICT OF COLUMBIA.

DESIGN FOR THE ORNAMENTATION OF FIRE-SCREENS, &c.

SPECIFICATION forming part of Design No. 17,234, dated April 5, 1887.

Application filed March 3, 1887. Serial No. 229,858. Term of patent 3½ years.

To all whom it may concern:

Be it known that I, JOHN MODINI, of Washington, in the District of Columbia, have invented a new Design for the Ornamentation of 5 Fire-Screens, &c.; and I do hereby declare that the following is a full, clear, and exact description thereof, reference being had to the accompanying drawing, and to the letters of reference marked thereon, which form part 10 of this specification.

The drawing accompanying this specification illustrates the general scope of my design for ornamentation of fire-screens, &c.

The leading features of my design consist 15 in a raised or bas-relief representation of a flowering bush rising from a vase-shaped figure situated near the lower edge, and about centrally of the length thereof, of the surface to be ornamented, and, further, in the representation of a pair of horseshoes placed one 20 on each side of said vase. These figures may be within a suitable border of ornamental work—such, for instance, as shown in the drawing.

25 A designates the base-piece or body of the screen or other surface to be ornamented. B designates a suitable ornamental border on the edges of said part A.

C designates a vase-shaped raised figure 30 situated centrally of the lower or front edge of part A.

D designates a raised design representing a flowering bush rising from the vase C, as shown.

E E designate figures of two raised horse-shoes, one on each side of the central vase. These representations of horseshoes may, if desired, be provided with epigrams suitably worked into their outer surfaces, as shown.

The figures of vase C, bush D, and horse-shoes E E form the principal features of my design.

F F designate small vase-shaped figures at the lower opposite corners of part A, and having vines G rising from them within the bordering B.

I claim—

1. The design for ornamenting fire-screens, &c., herein shown and described, consisting of the body A, having the vase-shaped figure 50 C, bush representation D, and horseshoe figures E E in relief.

2. The design for ornamenting fire-screens, &c., herein shown and described, consisting of the body A, having the vase-shaped figures 55 C and F F, bush representation D, and vine representation G G, and the horseshoe-shaped figures E E, one on each side of figure C, all said parts being in relief within a suitable border, B.

In testimony that I claim the foregoing as my own I affix my signature in presence of two witnesses.

JOHN MODINI.
